UNITED STATES PATENT OFFICE

JOHN S. STRINGFELLOW, OF LINDSAY, VIRGINIA

GATE

Application filed October 25, 1928. Serial No. 314,962.

This invention relates to closures and has special reference to gates extending across roadways, the object being to provide an improved construction of gate which may be 5 automatically opened by impact from a motor vehicle which is to pass, and which will be effectually held against premature closing without imposing excessive strain upon the gate. The invention also has for its object 10 the provision of novel means for effecting automatic return of the gate to closed position, and also the provision of a structure which will permit the gate to be swung in a horizontal plane as well as in a vertical plane 15 to permit pedestrians to pass or permit the passage of horses and their riders. The invention seeks further to provide a gate which will be light but strong and which will effectually operate in heavy weather or when the 20 ground is covered with snow. These stated objects, and other objects which will appear incidentally in the course of the following description, are attained in such a structure as is illustrated in the accompanying drawings, 25 and the invention resides in certain novel features which will be particularly pointed out in the appended claims.

In the drawings:

Figure 1 is a perspective view of a gate embodying my invention,

Fig. 2 is a sectional elevation showing the manner in which the gate is opened by an automobile to permit the passage of the automobile,

Fig. 3 is a detail perspective view of the means whereby the gate is mounted,

Fig. 4 is an enlarged sectional elevation of the device for holding the gate lowered or open until the automobile has fully cleared 40 the same,

Fig. 5 is an enlarged transverse section of the structure shown in Fig. 4,

Fig. 6 is an enlarged detail of a portion of the means for counter-balancing the gate and 45 normally holding it closed,

Fig. 7 is an enlarged detail sectional view through an end of the gate and the adjacent post, and

Fig. 8 is a view similar to Fig. 5, but showing a modified structure.

In carrying out the invention, there is provided at the opposite sides of a roadway, indicated at 1, uprights or posts 2 which may form the terminals of a fence 3 and at points spaced from the posts 2, preferably in the line of the fence, are stakes or shorter posts, one of which is shown at 4. Extending across the roadway in alignment with the posts 2 is a sill 5 which may be of any approved form and may be buried flush with the surface of the roadway or may be permitted to extend above the roadway and have its side edges beveled or otherwise shaped to permit easy passage of vehicle wheels thereover. Disposed above the sill 5 and normally resting thereon is a supplemental sill or bottom gate bar 6 which is provided at one end with a slot or elongated opening 7 to receive a pin or stud 8 fixed in the sill 5 and rising therefrom to constitute a vertical pivot for the gate when the occasion arises. At the opposite end of the sill 5 is a similar stud or pin 9 which, however, is of less height and which is received within a slot 10 in the bottom gate bar 6, the end of the slot 10 being closed by a keeper plate 11 of any convenient or approved form. The slot 7 may taper downwardly through the bottom bar 6 and on the under side of said bar there may be provided, if so desired, a wear plate upon which the bar may rock when it is necessary to clear the stud 9. The gate frame consists of a member 12 formed into substantially an open rectangle and constituting the top, bottom and end members of the gate. This frame member 12 may be formed from tubular material or may be a light rod, the only necessity being that it will be sufficiently strong and durable without having excessive weight. Upon the lower run 13 of the frame member 12 are secured spaced clamps 14 which have their lower portions formed into eyes or sleeves 15, and fixed to the bottom gate bar 6 are pintle elements or hooks 16 which extend longitudinally of said gate bar in spaced relation to 80 the top of the same and spaced apart a distance corresponding to the spacing of the clamps 14 whereby the clamps may be slid endwise into engagement with the pintle hooks and then serve to retain the gate 85

90

95

95

100

in proper position over the gate bar 6, and it will be obvious that, when the sleeves 15 and the pintles 16 are so engaged, the gate may rock in a vertical plane about the pintles as pivots. It will also be understood that if, 5 for any reason, it be desired to operate the gate in a horizontal plane all that needs to be done is to lift the gate sufficiently to permit the bar 6 to clear the pin or stud 9, a slight 10 longitudinal oscillation of the gate to effect such clearance being permitted by the elongated form of the slot 7 which receives the pin or stud 8. The pin or stud 8 is of such vertical dimension that it will always have 15 some part within the slot or opening 7 and after the stud 9 has been cleared the gate may be swung horizontally about the pin 8 as a pivot.

While the detail structure of the fence is 20 immaterial, it may be noted that it has been shown in the accompanying drawings as a wire fence which is very generally used. The gate is completed by affixing intersecting wires 17 to the frame member 12 in any convenient manner and in such number that 25 the entire area of the frame will be covered. The gate wires 17 should be provided in such number and so spaced that they will effectually prevent the passage of straying animals 30 and provide a gate of ample strength while minimizing wind resistance. At intermediate points in the length of the gate, I secure thereto track members or ladders, indicated generally by the numeral 18, which are so spaced 35 that they will be presented to the wheels of an automobile moving over the roadway 1 centrally or approximately centrally of the roadway. These ladders or track members comprise side bars 19 having their ends formed 40 into loops 20 which are passed around the top and bottom members of the gate frame and have their ends riveted or otherwise rigidly secured to their main portions at the inner sides of the respective members of the gate 45 frame. Extending between the parallel side bars 19 and fixed thereto in any approved manner are cross bars or rungs 21 which may be provided in any desired number. It will be noted that the side bars and the rungs lie close 50 to the gate wires so that they serve to counteract any tendency of the wires to sag or warp or flex through use. It will be understood, particularly upon reference to Fig. 2, that in 55 closed position the gate stands upright, as shown in Fig. 1, and the automobile is driven against the gate in the planes of the ladders or track members 18. The gate will, consequently, be caused to swing in a vertical plane away from the vehicle, as shown in Fig. 2, 60 and means are provided, to be presently described, to counterbalance the gate and return it to closed position as well as to prevent it prematurely closing. It should be observed, however, at this point that the track members 65 are of such form that they harmonize with

the general appearance of the gate and, therefore, do not detract from its attractiveness and, moreover, they do not appreciably add to the wind resistance so that the gate is not apt to be blown down even in very severe winds. 70 When the ground is covered with snow or is of a muddy consistency, the form of the ladders or tread members enables them to cut through the snow or mud so that the latter will not be packed and will not collect upon 75 the tread members to cause warping of the gate or of the tread members or add to the dead weight of the same or otherwise interfere with its easy successful operation.

As clearly shown in the drawings, the posts 2 are extended above the top of the gate and the fence and at the upper end of each post there is secured a bracket or bridle member 22 in which is suspended a guide roller or pulley 23, said roller or pulley being journaled in 80 the ends of a keeper 24 which is suspended from the top of the bracket 22 by a short chain 25, the pulley being thereby so mounted that it may move freely to conform to the varying 85 angular positions assumed by the cable 26. 90 It will be noted that a cable 26 is provided at each end of the gate and each cable has one end firmly secured to the top member of the gate frame at the end thereof, as shown at 95 27. From the pulley 23, the cable extends 100 downwardly and outwardly from the post and the gate and has its end secured to the stake or post 4 at or near the top of the same, the cable being of such length that, when the gate is closed, there will be a considerable portion of the same hanging loosely between the gate posts 2 and the adjacent cable retaining post 4. Secured upon the cable adjacent the end thereof are a plurality of 105 spaced counter-balance weights 28 which preferably successively increase in size in a direction away from the stake or post 4 and the length of the cable and the location of the several weights is such that the heaviest weight will be at the bottom of the loop 110 formed by the cable when the gate is closed and the other weights will be disposed at successively higher points along the outer side of the loop, as clearly shown in Fig. 1. The lowest weight will be of sufficient capacity to 115 maintain the gate normally closed in which position it will be nicely balanced. If no counter-balance were provided, the gate could be very easily pushed over and would move toward the ground with a constantly increasing force and would be apt to strike the ground with such an impact as would bend the gate and be very apt to damage it to such an extent that it would not operate. By providing the graduated system of weights, the 120 downwardly swinging movement of the gate will be checked by a gradually increasing force as each successive weight becomes active so that, while there will be a minimum resistance to the opening of the gate, there 125 130

will be a constantly increasing and effectual resistance to the opening movement which will attain its maximum force just prior to the gate reaching the ground, and damaging impact with the ground will be thereby avoided. The gate tends to rise and the counter-weights, of course, aid in the rising movement as soon as the vehicle has cleared the gate. With a fixed counter-weight of maximum capacity, the gate would be brought up violently and often would be carried past the closing position so that it would oscillate for a considerable period. With my present device, the lifting force is gradually diminished as the gate approaches the closed position so that just as the gate reaches the closing position the lifting force will cease and the gate will come to rest without oscillating.

A very strong objection to vertically swinging gates opened automatically by a passing vehicle has been the tendency of the gates to rise prematurely so that damage to the gate or to the vehicle frequently occurred. These accidents were frequent with large cars inasmuch as the front wheels of the car would clear the gate before the rear wheels engaged the same and the gate would swing upward against the chassis or running board or other part of the vehicle and breakage of parts would result. My present invention provides means whereby the premature closing of the gate is prevented. Midway between the ends of the gate frame, I secure thereto poles 29 which are provided in a pair extending vertically at the opposite sides of the gate and may be of tubular formation, as shown most clearly in Fig 5, and secured to the gate frame by clips 30 passed around the poles above and below the respective members of the gate frame, as shown most clearly in Fig 4. Above the gate frame, the poles diverge, as shown at 31, and they should be somewhat resilient so that they will tend to retain their divergent relation after having been compressed in use. A check chain 32 is attached to the divergent portions 31 of the poles to limit the separating movement thereof and a spring plate 33 is disposed between them, attached to one of them and bearing upon the other, so as to accentuate the resilient action of the poles. Secured upon the divergent portions of the poles are housing members 34 which are each substantial ly U-shaped in section and taper from their upper or outer ends to their lower or inner ends, straps 35 being attached to the outer sides of the poles and passing over the housing members to secure and hold them in place. As shown, the edges of these housing members overlap so that they will prevent access of dirt, snow or rain laterally into the space between the poles to accumulate therein and clog the operation. The overlapping edge portions of the housing members are held together by retaining bolts 36 passing trans-

versely through the housing and held therein by clamp nuts 37 disposed adjacent the opposite faces of the housing members in such manner that the bolts will be held against endwise movement and the housing members will be held in a proper overlapping relation while permitted to slide freely relative to each other, all as clearly shown in Fig. 5. To accommodate the relative sliding movement of the housing members, slots 38 are formed in the sides of the same and it may be understood that, while I have shown the slots in both members, it is not absolutely necessary that both members be slotted and, if preferred, the slots may be provided only in one member. As shown in Fig. 2, a shallow pit or gutter 40 is provided in the roadway at the center of the same and at such a distance from the gate that, when the gate is lowered to open position, as shown by dotted lines in Fig. 2, the then lower divergent pole member 31 will enter and rest in said gutter or pit while the mating pole member will project upwardly into the path of the axle of the car. Consequently, as the vehicle travels over the gate, the front axle will ride upon the upper edge portion of the pole and will thereby retain the gate in its closed position until the rear wheels of the vehicle have entered upon the gate and be in position to prevent the opening movement of the same. The resiliency of the free end portions of the poles permits the upper pole member to yield to the impact of the axle so that damage to the axle or the gate will be avoided and the retaining strap 35 also serves as a track member for the axle as it proceeds over the pole. It will also be noted that the extremities of the poles are turned inwardly, as shown at 41, whereby as they swing upwardly behind the vehicle they will avoid sharp contact therewith which might cause damage to some of the parts.

The novel counter-balancing means employed by me enables me to build a gate of light weight and it might ordinarily be opened by animals straying onto the roadway and pushing against the gate. To prevent such opening and subsequent loss of live stock, I provide upon the ends of the gate and upon the gate posts spurs or teeth 43, as shown clearly in Fig. 7, which are provided in sufficient number to extend the full height of the gate and in staggered relation upon the gate and the respective post. When the animal pushes against the gate, his nose will immediately rub against some of these spurs and the ensuing pricking will cause the animal to move back from the gate before the gate is opened. Ordinarily, the spurs need be provided only on one side of the gate which, of course, is the side presented to the field in which the animals are to be kept. It will be understood, however that, if necessary, the

spurs might be provided upon both sides of the gate and the posts.

While I contemplate building gates having my improvements embodied therein, it is obvious that the several improvements may be applied to existing gates of the vertically swinging type. While I prefer the two-part housing hereinbefore described and shown in Figs. 1 to 5 of the drawings, the invention may be embodied in other detail structure, and in Fig. 8, I have shown a one-piece housing 44, the side walls of which may be flexible so that as the pole members are caused to approach in the lowered position shown by dotted lines in Fig. 2, said side walls may buckle to accommodate the movement of the poles and when the retaining pressure is released they will resume their straight flat form shown in Fig. 4. This form of the invention embodies the leaf spring 33 shown in Fig. 4, although it may be noted that Fig. 8 shows somewhat more clearly the manner in which the spring is mounted, the ends thereof being formed into tapered teeth or spurs 45 entering openings 46 in the adjacent pole members. The restraining chain 32 may be attached to the pole members in any approved manner, but in Fig. 8 is shown as provided at its ends with pins 47 pivotally attached to the chains so that they may be pushed endwise through the openings 46 and then caused to engage the inner surfaces of the poles if the chain be pulled.

Having thus described the invention, I claim:

1. In a gate structure, the combination of gate posts, a gate frame mounted between the gate posts for swinging movement about horizontal pivots, cables attached to the ends of the gate frame and having their intermediate portions supported by the tops of the posts at points above the gate frame and their outer ends secured at points remote from the gate posts whereby the cables will loop between the said points and the posts, and a plurality of counterweights secured upon the cables and gradually diminishing in weight from the bottom of the looping portion of the cable toward the secured end thereof.

2. In a gate structure, the combination of a gate mounted for swinging movement about horizontal pivots, tread members secured upon the gate between the ends of the same and comprising side bars secured to the top and bottom elements of the gate frame, and spaced rungs fixed to and extending between said side bars.

3. In a gate structure, the combination of a gate mounted for swinging movement about horizontal pivots, and ladder-like track elements secured upon the gate frame parallel with and between the end members thereof.

4. In a gate structure, the combination

with a gate mounted for swinging movement in a vertical plane and adapted to be opened by a passing vehicle, of poles secured to the gate at the center of the same and extending beyond the top of the gate to be engaged by a passing vehicle when the gate is lowered and prevent premature rising of the gate, the extended portions of said poles being resilient.

5. In a gate structure, the combination of a gate mounted for swinging movement in a vertical plane, a check device secured to the gate and adapted to be engaged by a passing vehicle to resist closing movement of the gate, said checking device comprising diverging pole elements, means for yieldably holding said elements apart, and means for checking the movement of said elements from each other.

6. In a gate structure, the combination with a gate mounted for swinging movement in a vertical plane, of poles secured to the opposite sides of the gate and extending beyond the free edge thereof, the extending portions of said poles being divergent, means for yieldably maintaining said extending portions in divergent relation, and a housing extending around said divergent portions of said elements and constructed to accommodate movement of the elements toward each other.

7. In a gate structure, the combination with a gate mounted for swinging movement in a vertical plane, of poles secured to opposite sides of the gate and extending beyond the free edge thereof, the extending portions being divergent, yieldable means for moving the divergent portions apart, and a housing disposed about said divergent portions of the poles and constructed to telescope between the poles, and means securing the housings to the poles, said means providing track elements to be engaged by a portion of a vehicle passing over the gate when the latter is in lowered open position.

In testimony whereof I affix my signature.

JOHN S. STRINGFELLOW.
